CLAIM

The ornamental design for a shopping cart cover for baby, as shown and described.

DESCRIPTION

FIG. 1 is a top perspective view of a shopping cart cover for baby, showing my new design;

FIG. 2 is a bottom perspective view thereof;

FIG. 3 is a rear perspective view thereof;

FIG. 4 is a front view thereof;

FIG. 5 is a rear view thereof;

FIG. 6 is a left side view thereof;

FIG. 7 is a right side view thereof;

FIG. 8 is a top view thereof;

FIG. 9 is a bottom view thereof; and,

FIG. 10 is another perspective thereof; shown in an alternate configuration.

The thin broken lines in the drawings illustrate the portions of the shopping cart cover for baby, which form no part of the claimed design.

The thick broken lines representing stitching are part of the claimed design.

1 Claim, 10 Drawing Sheets
